UNITED STATES PATENT OFFICE

146,333

DESIGN FOR A LAWN MOWER HEAD

Eugene L. Boyce, Chicago, Ill., assignor to
H. Goldberg, Chicago, Ill.

Application February 11, 1946, Serial No. 126,483

Term of patent 14 years

(Cl. D40—1)

To all whom it may concern:

Be it known that I, Eugene L. Boyce, a citizen of the United States, residing at Chicago, in the county of Cook and State of Illinois, have invented a new, original, and ornamental Design for a Lawn Mower Head, of which the following is a specification, reference being had to the accompanying drawings, forming part thereof.

Figure 1 is a perspective view of the lawn mower head, illustrating the front, top and one end of the lawn mower head showing my new design; and

Figure 2 is another perspective view illustrating the top, the other end, and the rear of the lawn mower head.

I claim:

The ornamental design for a lawn mower head, as shown.

EUGENE L. BOYCE.
